United States Patent Office

Des. 207,066
Patented Feb. 28, 1967

207,066

IRON HOLDER

Raymond L. Nelson, 14200 Spring Lake Road,
Minnetonka, Minn. 55343

Filed June 6, 1966, Ser. No. 2,578

Term of patent 14 years

(Cl. D49—6)

FIG. 1 is a perspective view of an iron holder showing my new design.

FIG. 2 is a side elevation view thereof.

FIG. 3 is an enlarged top plan view thereof.

FIG. 4 is an enlarged elevational view thereof taken from the opposite side of FIG. 2.

FIG. 5 is a front elevation view thereof.

The broken line showings of the iron and ironingboard are for illustrative purposes only.

I claim:

The ornamental design for an iron holder, as shown and described.
